Primary Examiner — Paul D Bohannon*(74) Attorney, Agent, or Firm* — Michael Best & Friedrich LLP**CLAIM**

The ornamental design for an arm chair as shown and described.

DESCRIPTION

FIG. 1 is a perspective view of an arm chair.

FIG. 2 is a front view of the arm chair of FIG. 1.

FIG. 3 is a rear view of the arm chair of FIG. 1.

FIG. 4 is a first side view of the arm chair of FIG. 1.

FIG. 5 is a second side view of the arm chair of FIG. 1; and,

FIG. 6 is a top view of the arm chair of FIG. 1.

The broken lines shown in the drawings illustrate portions of the arm chair that form no part of the claimed design.

1 Claim, 6 Drawing Sheets(56)
